UNITED STATES PATENT OFFICE.

HENRY MALLEBRE, OF BALTIMORE, MARYLAND.

ADJUSTMENT FOR PIANO-ACTIONS.

SPECIFICATION forming part of Letters Patent No. 733,725, dated July 14, 1903.

Application filed April 10, 1903. Serial No. 151,979. (No model.)

To all whom it may concern:

Be it known that I, HENRY MALLEBRE, a citizen of the United States, residing at Baltimore, State of Maryland, have invented certain new and useful Improvements in Adjustments for Piano-Actions, of which the following is a specification.

This invention relates to improvements in adjustments for piano-actions.

10 The object of the invention is to provide an improved device for adjusting the key-frame and hammers with respect to the strings, whereby the quality of tone may be maintained or to increase the brilliancy of tone as 15 might be desirable in the temporary use of the piano for concert purposes.

With this object in view the improved device is illustrated in the accompanying drawings, in which—

20 Figure 1 is a sectional diagrammatic view of a portion of a piano employing my invention. Fig. 2 is a vertical longitudinal section through the key-block, and Fig. 3 is a vertical cross-section through one of the key-blocks and a portion of the key-frame. Fig. 25 4 is a detail view of the spring-clip for holding the key-frame.

In the drawings, A designates the key-bottom and B the key-frame, which has position 30 on said key-bottom and which is to be adjusted in a direction parallel with the strings. The keys, hammer-actions, and hammers are all mounted on the key-frame and move therewith. A key-block C has position at 35 each end of the key-frame, although but one is shown in the drawings. These key-blocks are stationary and are secured to the key-bottom, and in the present instance by dowels c and also by a screw c', which passes 40 up through the bottom and enters the block from the bottom. The strings D are strung cross-wise of the key-frame and above the latter in any suitable manner, and said strings have position between the agraffe E and hammers F.

The key-bottom A is provided with suitable spring-clips a, each of which is provided with a flange a', through which latter screws a² are passed into the key-bottom, and these 50 spring-clips are each provided with a rounded clamping-surface a³, which takes over the top surface of the key-frame and holds the lat-

ter down on the key-bottom, but permits the key-frame to have a sliding movement beneath said rounded surface.

55

The parts and mechanism so far described may have any suitable form and construction.

The key-blocks C are provided with a slot g, which has position in the side confronting the key-frame B, and this slot g extends 60 vertically from the bottom c² of said block. The key-block is also provided with a passage-way g', which extends in a direction at right angles to said slot g and extends across the latter and again enters the block at the 65 opposite side of said slot. This latter portion of the passage-way g' is provided with screw-threads g², for a purpose to be herein-after described. A pin h has one end secured in the side of the key-frame, and the other 70 end of said pin projects into the slot g of the key-block and has position in the path of the passage-way g'. A wood-screw i is provided with a circumferential groove j, and said screw extends through the passage-way g' 75 across the slot g and engages the threads g² in the passage-way of the stationary key-block beyond the said slot g. When in position, the circumferential groove j has position in the slot g, and the position of the groove in 80 said slot may be varied at will by turning the screw one way or the other. As clearly shown in Figs. 2 and 3, the circumferential groove of the screw i fits down over the projecting end of the pin h, and as the screw i is turned 85 the pin h will be moved forward or backward, according to the direction the screw moves, and by such movement the key-frame B is also moved in the same direction with the pin. It will therefore be clearly understood 90 that as the keys, hammer-actions, and hammers are all mounted on the key-frame any movement of the frame will cause a like movement to the parts mounted thereon, and therefore by turning the screw i the hammers F are moved backward or forward, as desired, beneath the strings D and agraffe E.

In order to provide for any wear that may occur to either the circumferential groove j or the pin h and to insure that the said pin 100 will always be in position in said groove, I have provided a vertical adjustment for the block C, whereby the latter and the screw i may be raised or lowered vertically to keep

the pin in engagement with the said groove. This adjusting device is simple and comprises two screws *k* and *k'*, the former being secured in the top surface of the key-bottom and the latter having position in the bottom surface of the key-block and both of said screws being in alinement. In order to adjust the key-block, and thereby cause the pin *h* to take in the circumferential groove *j*, either or both 10 of said screws *k* or *k'* may be turned in the proper direction to accomplish this adjustment and the key-frame is kept close to the key-bottom to prevent rattling.

It is obvious that the screw *i*, slot *g*, and 15 passage-way *g'* may be arranged in the key-frame and the pin *h* arranged in the key-block.

Having thus fully described my invention, what I claim as new, and desire to secure by Letters Patent, is—

20 1. In a piano the combination of the strings; the key-block having a vertical slot and a passage-way extending across said slot; a screw in said passage-way and extending across said vertical slot, said screw having a circumferential groove which registers with said vertical slot; a key-frame; the hammers and hammer-action supported by said key-frame, and a pin carried by said key-frame and projecting into the vertical slot of the key-block and 25 30 engaging the groove of said screw for the purpose set forth.

2. In a piano the combination of the strings; the key-block; a key-frame; the hammers and hammer-action supported by said key-frame;

a screw in said key-block having a circumferential groove; a pin carried by said key-frame for engaging the groove of said screw, and means for vertically adjusting the key-block and the screw to overcome the wear of the pin in the groove of said screw.

3. In a piano the combination of a key-bottom; a key-frame movable on said key-bottom; the hammers and hammer-action supported by said key-frame; the strings; the key-block; one or more screws for vertically adjusting the key-blocks with respect to the key-bottom; a screw having a circumferential groove, and a pin engaging the groove of said screw, said screw and pin coacting between the key-frame and the key-block for the purpose set forth.

4. In a piano the combination of the strings; the key-blocks; a key-frame; the hammers and hammer-action supported by said key-frame; a screw in said key-block and having a circumferential groove; a pin on the forward end of said key-frame for engaging the groove of said screw to horizontally adjust the key-frame and to keep the forward end of the key-frame on the key-bottom, and one or more spring-clips secured to the key-bottom and 5! taking over the key-frame to hold the rear end of the key-frame down on said key-bottom.

In testimony whereof I affix my signature in the presence of two witnesses.

HENRY MALLEBRE.
